(57) **CLAIM**

The ornamental design for a sauce leveler device, as shown and described.

DESCRIPTION

FIG. 1 is a top perspective view of the sauce leveler device; FIG. 2 is a top view of the sauce leveler device according to FIG. 1;

FIG. 3 is a bottom view of the sauce leveler device according to FIG. 1;

FIG. 4 is a bottom view of the sauce leveler device according to FIG. 3 with the broken lines directed to the environment removed;

FIG. 5 is a back view of the sauce leveler device according to FIG. 1;

FIG. 6 is a front view of the sauce leveler device according to FIG. 1;

FIG. 7 is a right side view of the sauce leveler device according to FIG. 1; and,

FIG. 8 is a left side view of the sauce leveler device according to FIG. 1.

The broken lines immediately adjacent the shaded areas represent the bounds of the claimed design while all other broken lines are directed to environment and are for illustrative purposes only; the broken lines form no part of the claimed design.
